US00D896185S

(12) **United States Design Patent** (10) Patent No.: **US D896,185 S**
(45) Date of Patent: **** Sep. 15, 2020**

(54) **TWO IN ONE CONNECTOR**

(71) Applicant: **SARIANA, LLC**, San Diego, CA (US)

(72) Inventors: **Alan Turksu**, San Diego, CA (US);
Mustafa Burak Guclu, San Diego, CA (US)

(73) Assignee: **SARIANA, LLC**, San Diego, CA (US)

(57) **CLAIM**

What is claimed is the ornamental design for a two in one connector, as shown and described.

DESCRIPTION

FIG. 1 is a front, top, left perspective view of a two in one connector showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof; wherein the broken lines are for illustrative purposes only and form no part of the claimed design.
